COMBINED HAND CARRIED LIGHTING UNIT AND MAGNETIC BASE THEREFOR

James W. Lang, 4523 Jennings,
Wichita Falls, Tex. 76310

Filed Apr. 26, 1973, Ser. No. 354,521

Term of patent 14 years

Int. Cl. D26—02
U.S. Cl. D48—24 R

FIG. 1

FIG. 2

FIG. 3

FIG. 4

FIG. 5

FIG. 6

FIG. 1 is a side elevational view of a combined hand carried lighting unit and magnetic base therefor showing my new design;

FIG. 2 is an opposite side elevational view thereof;

FIG. 3 is a bottom plan view thereof;

FIG. 4 is a top plan view thereof;

FIG. 5 is a front elevational view thereof; and

FIG. 6 is a rear elevational view thereof.

I claim:

The ornamental design for a combined hand carried lighting unit and magnetic base therefor, as shown.
